CLAIM

The ornamental design for connector holder, as shown and described.

DESCRIPTION

FIG. 1 is a front view of a connector holder showing our new design;

FIG. 2 is a rear view thereof;

FIG. 3 is a top plain view thereof;

FIG. 4 is a bottom view thereof;

FIG. 5 is a left side view thereof;

FIG. 6 is a right side view thereof;

FIG. 7 is a perspective reference view of the front, left and top of connector holder showing our new design;

FIG. 8 is a perspective reference view of usage; and,

FIG. 9 is a perspective reference view of usage in the open condition.

The portions shown in broken lines are for illustrative purposes only and form no part of the claimed design.
